UNITED STATES PATENT OFFICE.

HARRY C. ADAM, OF ST. LOUIS, MISSOURI.

SEMI-INDIRECT-LIGHTING FIXTURE.

1,178,201.

Specification of Letters Patent.

Patented Apr. 4, 1916.

Application filed January 24, 1916. Serial No. 73,962.

To all whom it may concern:

Be it known that I, HARRY C. ADAM, a citizen of the United States, residing at St. Louis, Missouri, have invented a certain new and useful Improvement in Semi-Indirect-Lighting Fixtures, of which the following is a full, clear, and exact description, such as will enable others skilled in the art to which it appertains to make and use the same.

This invention relates to semi-indirect lighting fixtures, and has for its main object to provide a semi-indirect lighting fixture which is so constructed that the rays of light from the lighting unit will be distributed in a novel manner that produces a strong light directly beneath the fixture and a diffused light on the ceiling from which the fixture is suspended.

Another object is to provide a semi-indirect lighting fixture in which the top reflector and the diffusing shield or bowl under the lighting unit are supported in a novel manner which makes it possible to install or remove said members quickly and easily. And still another object is to provide a device of novel construction for detachably connecting the top reflector of a direct or semi-indirect lighting fixture to the supporting structure that carries same.

Other objects and desirable features of my invention will be hereinafter pointed out.

Figure 1 of the drawings is an elevational view, partly broken away, of a lighting fixture constructed in accordance with my invention. Fig. 2 is a detail view, partly in vertical section, of the means used in the fixture shown in Fig. 1 for supporting the top reflector and the bottom diffusing shield, and Fig. 3 is a perspective view of the clip that forms part of said means.

Referring to the drawings, which illustrate the preferred form of my invention, A designates the top reflector of a semi-indirect lighting fixture, B designates a translucent diffusing shield or bowl that is arranged underneath said top reflector and C designates the lighting unit of the fixture, herein shown as an electric lamp bulb. The top reflector A is provided with two oppositely-inclined reflecting surfaces x and y that are arranged between the outer edge of the top reflector A and an opening 1 at the center of said top reflector up through

which a portion of the lighting unit C passes. The reflecting surface x, which is preferably curved slightly, slopes upwardly from the outer edge of the top reflector A and merges into the reflecting surface y, which slopes upwardly from the center opening 1 in the top reflector, thereby producing a reflecting surface on the top reflector A that causes the rays from the lighting unit to be projected downwardly in such a manner that a strong light is produced directly beneath the fixture. Some of the rays from the lighting unit that strike the reflecting surface x on the top reflector are projected downwardly directly beneath the fixture and other rays that strike the oppositely inclined reflecting surface y on the top reflector are projected downwardly and laterally toward the side walls of the room. The upper edge of the diffusing shield B is arranged near enough to the top reflector A to insure the rays that pass over the upper edge of the shield B striking against the reflecting surface x on the top reflector, thus preventing any rays from the lighting unit from escaping without striking either the shield or the top reflector.

The center opening 1 of the top reflector permits some of the rays from the lighting unit to pass upwardly and illuminate the space above the top reflector A, and in order to prevent these rays from producing an intense glare or bright ring on the ceiling directly above the top reflector, I have provided the fixture with a top diffusing shield D arranged in such a manner that the rays passing upwardly through the center opening 1 of the top reflector will be diffused, and thus produce a soft light on the ceiling. This top diffusing shield D is formed of opalescent glass, or some other translucent substance, and it is curved slightly in an arc that is approximately concentric with the filament of the lighting unit, so as to insure the upward rays passing directly through same instead of striking the underside of the shield D and glancing off at an angle. The top diffusing shield D is preferably made considerably larger than the center opening 1 in the top reflector, and the lower edge of said shield is arranged in engagement with or in close proximity to the top side of the portion of the top reflector that surrounds the center opening 1 in the top reflector. By arranging the top diffusing

shield D in this manner I eliminate the possibility of any upward rays from the lighting unit striking the ceiling, without first passing through a diffusing member, and I prevent dust and dirt from dropping through the center opening on the top reflector and collecting on the lighting unit.

In a lighting fixture of the construction above described practically all of the rays 10 from the lighting unit are utilized and the rays are distributed in such a manner that a strong light is produced directly beneath the fixture and a soft, diffused light is produced on the ceiling of the room in which 15 the fixture is suspended. I realize that it has long been the practice to arrange a lighting unit between an upper and a lower diffusing shield of translucent material, but my improved fixture is distinguished from a lighting fixture of the kind just referred to, in 20 that it is composed of a top and a bottom diffusing shield arranged above and below the source of light, respectively, and a top reflector arranged between said diffusing 25 shields and provided adjacent its outer edge with an upwardly-inclined reflecting surface that projects the rays downwardly beneath the fixture, and adjacent its center with an oppositely-inclined reflecting surface 30 that serves to project the rays downwardly and laterally toward the side walls of the room.

It is immaterial, so far as my broad idea is concerned, how the top reflector A and 35 the top and bottom diffusing shields D and B are supported, but I prefer to connect the top diffusing shield D to a shell or husk 2 that incases an electric lamp socket 3 which carries the lighting unit C, said shell 2 being secured to a device that depends from 40 the ceiling, such, for example, as a chain 4. The bottom diffusing shield B is suspended from short chains, links or rods 5 which are connected at their upper ends to a supporting 45 structure that carries the top reflector A, said supporting structure preferably consisting of a plurality of chains or other suitable devices 6 that depend from the ceiling and which are provided at their lower ends 50 with detachable clips E to which the top reflector A is clamped. The chains 6 that carry the top reflector and the bottom diffusing shield, and the center chain 4 that carries the shell 2 to which the top diffusing 55 shield is connected, have their upper ends secured to a canopy 7 on the ceiling, as shown in Fig. 1. Each of the clips E is substantially yoke-shaped, as shown in Fig. 3, and the cross piece 8 of same is provided 60 with a hole 9 for receiving the screw-threaded shank of a bolt 10 that clamps the clip to the top reflector A. The bolt 10 passes through an opening in the top reflector A and through the opening 9 in the cross piece 65 of its coöperating clip, and a nut 11 is

mounted on the shank of the bolt above said cross piece, as shown in Fig. 2, so as to draw the bolt upwardly, and thus securely clamp the top reflector A between the cross piece 8 of the clip and a head 12 on the bolt. At 70 the lower end of the bolt is an eye or ring 13, to which the suspending link 5 for the bottom diffusing shield is joined in any suitable manner. The two side pieces 14 of each of the clips E are bent inwardly toward each other, as shown in Fig. 3, so that they will lie between the side portions of the bottom link of the chain 6 to which the clip is connected, and each of said side pieces is provided with a horizontally-disposed slot 15 80 through which the lower end portion of the chain link passes, the slot 15 in one of the side pieces of the clip extending inwardly from one edge of same and the slot 15 in the other side piece of the link extending inwardly from the opposite side of the clip, as shown in Fig. 3, said slots 15 being provided at their inner ends with enlarged portions 15^a so as to prevent the clip from twisting or turning with relation to 90 the chain 6 to which it is connected. To attach the clip to its coöperating chain 6 the bottom link of the chain is first inserted between the side pieces 14 of the clip, and the link is then given a quarter turn, so that it will lie at right angles to the side pieces of the clip in the enlarged portions of the slots 15 in the clip. If desired, the side pieces of the clip can be cut away at 16 or provided with openings, as shown in Figs. 2 and 3, so 95 as to eliminate the possibility of the end of the shank of the bolt 10 bearing against the clip.

In assembling the fixture the clips E are first securely clamped to the top reflector A 100 by means of the bolts 10, and the links at the lower ends of the chains 6 are then slipped into operative position in the cross slots of the clips. Thereafter, the bottom diffusing shield D is connected to the eyes or 105 rings 13 on the lower ends of the bolts 10 by means of the short links or chains 5 from which the bottom shield is suspended. The top diffusing shield D and the lighting unit C are both carried by a chain or other suitable device 4 that is separate and distinct 110 from the chains that support the top reflector and the bottom diffusing shield, thus facilitating the installation of the fixture and the removal of same.

The clips E are preferably stamped out of sheet metal, and accordingly, they can be manufactured at a low cost, and as they can be connected to or disconnected from the chains 6 without inserting or removing separate fastening devices and without opening the links of the chains 6, they form a very efficient means for connecting the top reflector of an indirect or semi-indirect lighting fixture to supporting chains.

Having thus described my invention, what I claim, and desire to secure by Letters Patent, is:

1. A lighting fixture, comprising a top reflector provided with oppositely-inclined reflecting surfaces and having a center opening up through which rays from the lighting unit of the fixture pass, a translucent diffusing shield arranged under said top reflector beneath the lighting unit, and a top diffusing shield of translucent material arranged over the center opening in the top reflector and curved on an arc that is approximately concentric with the source of light.
2. In a lighting fixture, a top reflector provided with a center opening and oppositely-inclined reflecting surfaces arranged intermediate said center opening and the outer edge of the reflector, a diffusing shield arranged underneath said top reflector, means for sustaining said top reflector and shield in operative position, a shell arranged above the top reflector and provided with a top diffusing shield of translucent material that extends over the center opening in the top reflector, an electric lamp socket carried by said shell, and a separate and distinct means for sustaining said shell in operative position.
3. In a lighting fixture, a top reflector, a supporting structure, and a yoke-shaped clip on the upper side of said top reflector whose side portions have horizontally-disposed slots for receiving an element on said supporting structure that is arranged at substantially right angles to the side portions of the clip.
4. In a lighting fixture, a top reflector, a chain from which said top reflector is suspended, and a yoke-shaped clip on the upper side of said top reflector whose side portions have horizontally-disposed slots that extend inwardly from opposite edges of the clip so as to permit the clip to be connected to one link of said chain by introducing the link between the side portions of the clip and then giving one of said elements a quarter turn with relation to the other.
5. In a lighting fixture, a top reflector, a supporting means, and a clip on the upper side of said top reflector for detachably connecting it to said supporting means, said clip consisting of a substantially yoke-shaped device whose cross piece is provided with an opening for receiving a fastening device that connects the clip to the top reflector and whose side portions have horizontally-disposed slots that extend inwardly from opposite sides of the clip.

In testimony whereof I hereunto affix my signature in the presence of two witnesses, this twenty-first day of January, 1916.

HARRY C. ADAM.
